UNITED STATES PATENT OFFICE.

ISAAC N. DANN, OF NEW HAVEN, CONNECTICUT, ASSIGNOR TO THE NEW HAVEN FOLDING CHAIR COMPANY, OF SAME PLACE.

DESIGN FOR A CHAIR-SEAT.

SPECIFICATION forming part of Design No. 12,133, dated January 18, 1881.

Application filed December 20, 1880. Term of patent 3½ years.

To all whom it may concern:

Be it known that I, ISAAC N. DANN, of New Haven, in the county of New Haven and State of Connecticut, have invented a new Design 5 for Chair-Seat; and I do hereby declare the following, when taken in connection with the accompanying drawing and the letters of reference marked thereon, to be a full, clear, and exact description of the same, and which said 10 drawing constitutes part of this specification, and represents a full view of one seat and partial views of adjacent seats in same web.

This invention relates to a design for seats for that class of chairs commonly called "folding chairs," and which require that the seat 15 shall be flexible. For the best class of these chairs the seats are woven in patterns or figures which are complete in themselves for a single seat, in contradistinction to a continuous 20 figure, as in carpets, which are cut into pieces irrespective of the figure; and the design consists in the pattern for a single seat shown in the accompanying illustration.

A is the ground of the seat, which may be 25 of a single color or slightly figured. On this

ground a base is represented as composed of a series of points, and over these a border-line of "Grecian-key" pattern. Appearing as in rear of this base is the representation of water. In the center stands the representation of a crane, 30 with leaves and branches of flag at the right and left, all as shown in the accompanying illustration.

The figure which forms the base may be changed somewhat without departing from 35 the general features of this design, it only being essential that it shall be the representation of a base or wall in front of water.

These seats are woven in a continuous web in the usual manner for pattern chair-seats. 40

I claim—

The design for woven chair-seats, consisting in the representation of a wall or base in front of water, in which is the representation of a crane with leaves and branches of flag, all as 45 shown in the accompanying illustration.

ISAAC N. DANN.
